UNITED STATES PATENT OFFICE.

PAUL H. ZIMMER, OF SCHENECTADY, NEW YORK, ASSIGNOR TO GENERAL ELECTRIC COMPANY, A CORPORATION OF NEW YORK.

RHEOSTAT.

No. 901,512.

Specification of Letters Patent.

Patented Oct. 20, 1905.

Application filed May 20, 1907. Serial No. 374,549.

To all whom it may concern:

Be it known that I, PAUL H. ZIMMER, a citizen of the United States, residing at Schenectady, county of Schenectady, State 5 of New York, have invented certain new and useful Improvements in Rheostats, of which the following is a specification.

This invention relates to means for controlling electric circuits and has for its object the provision of a device of this character which will start the motor and regulate 10 the speed thereof in a reliable, safe and efficient manner.

One of the objects of my invention is to 15 provide an improved rheostat by means of which the motor may be brought up to running speed through a starting resistance and the speed then controlled through another resistance, preferably in the motor field circuit, the arrangement being such that the field strength cannot be varied until running conditions have been established in the armature circuit.

Other objects of my invention will appear 20 in the course of the following specification, in which I have shown my invention embodied in two different forms for purposes of illustration.

In the drawings, Figure 1 is a plan view 25 of the rheostat embodying one form of my invention and showing the arrangement of circuits; Fig. 2 is a view showing the working parts in operative position; Fig. 3 is a plan view of a modified form of my invention; and Fig. 4 is a view showing the working parts in starting position.

Referring first to Figs. 1 and 2, 10 is an insulating base of slate or soap-stone provided with a series of contacts 11 arranged 30 in an arc of a circle and forming the terminals of the starting resistance 12. Contacts 13 forming the terminals of the regulating resistance 15 and contact 14 are arranged concentrically with the studs 11, and a controlling arm 16 pivoted at 17 and provided with an operating handle 18 is adapted to sweep over and simultaneously engage these contacts. A disk 19 is rotatably mounted upon the pivot 17 so as to move independently of the arm 16. This disk is biased or spring-pressed to move in a counter-clockwise direction by means of the spring 20, one end of which bears against the stop 21 while the other end bears against the pin 22 35 mounted upon the disk 19. This pin projects

upward from the disk and abuts against the arm 16 so that the arm has a bias in a counter-clockwise direction so as to normally engage the stop 21. A controlling element or switch lever 23 is pivoted in proximity to 60 the arm 16 at 24 and at its outer end engages contacts 25 and 26 arranged in an arc of a circle of which 24 is the center, and separated by dead contacts 27. The lever 23 is likewise biased or spring-pressed by means of a 65 spring 28 which normally presses it in a clockwise direction against the stop 29. The lever is extended beyond the pivot so as to form an armature portion 30 coöperating with a no-voltage magnet 31. A projecting 70 portion or shoulder 32 is secured to the arm 23 and is so formed and arranged as to engage and hold the pin 22 from the arm 16 in the position shown in Fig. 1 in which position it is held by the retaining magnet. 75

The arrangement of circuits and the mode of operation of this form of my invention are as follows: Normally the lever 23 rests upon contact 26 and arm 16 rests upon dead segment 33 and dead stud 34, the moving parts being in the position shown in Fig. 4. When the line circuit is closed, the field is first energized from the positive, main through conductor 35, field F, conductor 36 to stud 26 thence through the lever 23 and conductor 37 back to the negative main. At the same time the magnet 31 is connected across the line through conductor 38, resistance R, conductor 39 and conductor 40 back to the negative main. As the arm 16 is 80 moved towards the right and engages the first of the studs 11, the armature circuit is closed as follows: From the positive main through armature A, conductor 41 to stud 25, thence through resistance 12, arm 16 and 85 conductor 37 back to line. As the arm is moved farther to the right, the starting resistance is gradually cut out, the field resistance being in the meantime short-circuited. When the arm 16 approaches the 90 limit of its movement, the pin 22 engages the shoulder 32 and moves the lever 23 into engagement with the retaining magnet so that its outer end rests on the stud 25. The curved portion of the shoulder passes over 95 the pin 22 and holds the disk in the position shown in Fig. 2. The armature resistance is now short-circuited, the current passing from stud 25 directly through lever 23 to the pivot 17 instead of through the resist- 100 105 110

ance and arm 16. At the same time the short-circuit of the field resistance is broken at contact 26 so that the field circuit instead of going from conductor 36 and stud 26 5 through the lever 23, passes from the conductor 36 at 42 to the field resistance 15, thence through the arm 16 and back to line. The arm may now be moved backward in a counter-clockwise direction to speed up the 10 motor by decreasing the field resistance without varying the armature resistance, there being no spring tension upon the arm. Upon failure of voltage the arm 16 and lever 23 return to their protective positions in response to their bias so that the parts are 15 again in a position for starting. The motor may also be stopped by moving the arm 16 backward over all of the studs 13 until it bridges the first stud 13 and stud 14. When 20 these two studs are bridged the magnet 31 is short-circuited and the parts automatically return to starting position.

In Figs. 3 and 4 I have shown my invention applied to a rheostat in which only a 25 single step of resistance is used in the armature circuit. This resistance 12' is cut out by the lever 23' when the latter is moved from stud 43 to stud 25'. In this form of my invention when the line circuit is closed 30 the field is energized as follows: From the positive main through conductor 44, lever 23', stud 26', conductor 45, field F, conductor 46 and back to the negative main. As the arm 16' is moved to the right the field 35 resistance 15' is short-circuited but the armature resistance is not closed until the arm 16 approaches the limit of its movement and the element 23' is shifted from stud 26' to stud 43. The direction of the current 40 through the armature is then as follows: From the positive main through conductor 44, lever 23; stud 43, starting resistance 12', conductor 47, armature A, conductor 46 and back to the negative main. At the same time 45 the short circuit of the field resistance is broken at 26' in the same manner as in the form shown in Fig. 1. As the arm 16' is moved farther to the right, the lever 23' leaves stud 43 and passes on to stud 25' 50 thereby short-circuiting the starting resistance 12' and placing the motor armature directly on the line. Upon failure of voltage the parts are returned to their starting position as before described, and the motor 55 may also be stopped by bridging contact 13' and contact 48 which short-circuits the retaining magnet 31'.

It will be seen that I have provided simple and reliable means for starting and controlling the speed of a motor, which means 60 will be automatically returned to a protective position, it being impossible for the parts to be operated in any other than the proper way.

65 Various modifications of my invention will

suggest themselves to those skilled in the art, all of which come within the spirit of my invention, in so far as they fall within the scope of the claims annexed hereto.

What I claim as new and desire to secure 70 by Letters Patent of the United States, is,—

1. A rheostat comprising resistance contacts, a controlling arm therefor spring-pressed towards its initial position, a circuit controlling element independently 75 spring-pressed and arranged to hold the spring pressure from said arm, and a no-voltage magnet for retaining the element in a holding position.

2. A rheostat comprising resistance contacts, circuit controlling elements biased to rotate in opposite directions, a no-voltage magnet for retaining one of said elements in a predetermined position, and means whereby the bias is removed from the other element 80 when the said position is reached.

3. A rheostat comprising resistance contacts, a controlling arm biased to rotate in a predetermined direction, a circuit controlling element biased to rotate in an opposite 90 direction, a no-voltage magnet for retaining said element in a biased position, and means whereby the bias is removed from the controlling arm when said element reaches the biased position.

4. A rheostat comprising resistance contacts, a controlling arm therefor, a spring-pressed member arranged to normally engage said arm and bias it towards a predetermined position, a circuit controlling element arranged to hold said member out of engagement with said arm, and a no-voltage magnet for retaining said element in a holding position.

5. A rheostat comprising resistance contacts, a controlling arm biased to rotate in a predetermined direction, a circuit controlling element arranged to be engaged by said arm and rotated in the same direction, means whereby the bias is removed from the controlling arm when said element reaches a predetermined position, and a no-voltage magnet for retaining the element in said position.

6. A rheostat comprising resistance contacts, a controlling arm biased to rotate towards an initial position, a circuit controlling element biased to rotate in an opposite direction and arranged to be engaged by said arm and moved against its bias to a predetermined position, means whereby the bias is removed from the controlling arm when said element reaches said position, and a no-voltage magnet for retaining the element in said position.

7. A rheostat comprising resistance contacts, a controlling arm spring-pressed towards an initial position, a circuit controlling element spring-pressed in an opposite direction towards an initial position and ar- 130

ranged to be engaged by said arm and moved against its spring tension to a second position, means whereby the said element holds the spring tension from the arm when it reaches said second position, and a no-voltage magnet for retaining the element in said position.

8. A rheostat comprising resistance contacts, a controlling arm therefor, a spring-pressed member arranged to normally engage said arm and bias it towards a predetermined position, a circuit controlling element arranged to be rotated to a predetermined position by the movement of the arm, means whereby said element engages said member and holds the spring tension from the arm when the element reaches said position, and a no-voltage magnet for retaining the element in a holding position.

20 9. A rheostat comprising a pair of resistances provided with contacts, a controlling arm simultaneously engaging said contacts and spring-pressed toward its initial position, a circuit controlling element arranged to hold the spring pressure from said arm, and a no-voltage magnet for retaining the element in a holding position.

10 10. A rheostat comprising a pair of resistances provided with contacts, a controlling arm simultaneously engaging said contacts, a spring-pressed member arranged to normally engage said arm and bias it towards its initial position, a circuit controlling element arranged to hold said member out of engagement with said arm, and a no-voltage magnet for retaining said element in a holding position.

11. A starting rheostat comprising a starting resistance and a field resistance each provided with contacts, a controlling arm simultaneously engaging said contacts and spring-pressed towards its starting position, a circuit controlling element arranged to hold the spring pressure from said arm, and a no-voltage magnet for retaining the element in a holding position.

12. A starting rheostat comprising a starting resistance and a field resistance each provided with contacts, a controlling arm simultaneously engaging said contacts, a spring-pressed member arranged to normally engage said arm and bias it towards the start-

ing position, a circuit controlling element arranged to hold said member out of engagement with said arm, and a no-voltage magnet for retaining said element in a holding position.

13. A starting rheostat comprising a starting resistance and a field resistance each provided with contacts, a controlling arm simultaneously engaging said contacts and spring-pressed towards the starting position, a circuit controlling element arranged to be engaged by said arm when the latter is moved to running position and be moved thereby to a predetermined position, means whereby the element holds the spring pressure from the arm when the element reaches said position, and a no-voltage magnet for retaining the element in a holding position.

14. A starting rheostat comprising a starting resistance and a field resistance each provided with contacts, a controlling arm simultaneously engaging said contacts, a spring-pressed member arranged to normally engage said arm and bias it towards a predetermined position, a circuit controlling element arranged to be moved to a predetermined position by said arm, means whereby said element engages and holds said member when the element reaches said position, and a no-voltage magnet for retaining said element in a holding position.

15. A starting rheostat comprising a starting and a field resistance each provided with contacts, a controlling arm simultaneously engaging said contacts, a spring-pressed member arranged to normally engage said arm and bias it towards its starting position, a circuit controlling element spring-pressed in an opposite direction towards its initial position and arranged to be moved to a predetermined position by the movement of said arm, means whereby said element engages and holds said member when the element reaches said position, and a no-voltage magnet for retaining said element in a holding position.

In witness whereof, I have hereunto set my hand this 18th day of May, 1907.

PAUL H. ZIMMER.
